US00D804627S

(12) **United States Design Patent** (10) Patent No.: **US D804,627 S**
Puffer et al. (45) Date of Patent: ** Dec. 5, 2017

(54) **VENT HOOD**(71) Applicant: **Broan-NuTone LLC**, Hartford, WI (US)(72) Inventors: **Benjamin Thorpe Puffer**, Hartford, WI (US); **Hyuk-Jae Chang**, Pittsburgh, PA (US)(73) Assignee: **BROAN-NUTONE LLC**, Hartford, WI (US)(**) Term: **15 Years**(21) Appl. No.: **29/527,420**(22) Filed: **May 19, 2015**(51) LOC (10) Cl. **23-04**

(52) U.S. Cl.

USPC **D23/371**

(57) **CLAIM**

The ornamental design for a vent hood, as shown and described.

DESCRIPTION

FIG. 1 is a top perspective of a first embodiment of the invention.

FIG. 2 is a bottom perspective of a first embodiment of the invention.

FIG. 3 is a top view of a first embodiment of the invention.

FIG. 4 is a front view of a first embodiment of the invention.

FIG. 5 is a bottom view of a first embodiment of the invention.

FIG. 6 is a back view of a first embodiment of the invention.

FIG. 7 is a left view of a first embodiment of the invention; and,

FIG. 8 is a right view of a first embodiment of the invention.

1 Claim, 8 Drawing Sheets
